UNITED STATES PATENT OFFICE.

WILLIAM A. LORENZ, OF HARTFORD, CONNECTICUT, ASSIGNOR TO UNITED STATES HAT MACHINERY CORPORATION, OF RICHMOND, VIRGINIA, A CORPORATION OF VIRGINIA.

APPARATUS FOR RAISING NAP ON HAT BODIES.

Application filed April 23, 1920. Serial No. 376,075.

To all whom it may concern:

Be it known that I, WILLIAM A. LORENZ, a citizen of the United States, residing at Hartford, in the county of Hartford and 5 State of Connecticut, have invented new and useful Improvements in Apparatus for Raising Nap on Hat Bodies, of which the following is a specification.

This invention relates to a process for 10 raising the nap on a fur hat body. In the present art the hat body is shrunken in the usual manner so as to form a body having some strength.

In order to raise the nap on this hat body 15 in order to produce a "velours" hat, the hat body is usually held upon a board after being dipped in hot water and it is scrubbed by means of a bristles brush in such a manner that the nap will be raised. After doing 20 this on one side, the other side is done. Then the hat body is opened up and folded crosswise and the operation is continued until the proper amount of fur has been raised on the body. Then the body is dried 25 and the nap is raised and sheared so as to remove the long ends.

The nap raising is then continued, the completed hat body is dried and the nap is sheared to the length desired. This is a 30 very slow and costly operation. It can readily be seen that to scrub the body with a bristles brush forces the fur inwardly rather than outwardly. A peculiar motion, however, is given to the brush so as to raise 35 the nap.

In the present process the hat body after 40 being shrunken to the proper density is placed upon a perforated cone and is held upon that cone by suction or otherwise. Then the surface of the hat body is brushed by means of a bristles brush conforming to the shape of the surface of the cone either at the side or at the top, or both. These 45 brushes are connected to a head which is hollow and this hollow head is connected to a vacuum producing apparatus such as a vacuum pump. After wetting the fur body and then applying the vacuum brush to the surface of the hat body the scrubbing will 50 be performed and at the same time the fur which is loosened on the hat body will be raised by means of the vacuum, which is sufficiently strong for the purpose.

In the drawings Figure 1 represents a side

view of the apparatus, part of which is in 55 section. Fig. 2 represents a plan view of the cone and Figs. 3, 4 and 5 represent the brushes which operate on the sides of the apparatus. The remainder of the machine, however, is omitted for the sake of clearness. In Fig. 1 the cone upon which the hat body is placed is shown partly in section and partly with fur on the outside of the cone. In Fig. 2 the hat body is shown on the cone.

In the drawings an upright 5 is shown 60 having a projecting bracket 6 partly shown in section, for supporting the cone table 7. This table 7 is rotated at the desired speed, which is slow; or it may be moved step by step; in the present instance it is moved by 65 means of a pair of bevel gears 8, one of which is attached to the shaft 9, the other bevel being attached to a shaft 10, to which is secured a driving pulley 11. The shaft 9 is made hollow at 12 and connects by means 70 of a pipe 13 with means for exhausting air from the interior of the cone 15. This cone is perforated at 16 with numerous holes and a fur hat body 17 is placed upon this cone. By exhausting the air sufficiently from the 80 interior of the cone the hat body will be held to the cone. The invention is not limited to the means illustrated for holding the hat body on the cone.

A vertical pipe 20 is supported in a frame 85 5, and has its lower end connected by means of a pipe 21 with an exhausting apparatus. This pipe 20 supports various instrumentalities as follows:

Above the cone 15 is placed an annular 90 perforated ring 22, which is hollow at 23 and whose inner face preferably may be conical. A hot water supply pipe 24 is connected to the ring 22 for admitting hot water to the ring 22 and spraying the hat 95 body with this hot water at desired intervals. This spraying is preferably done when all the brushes, to be described later, are removed from the cone.

An arm 30 is mounted upon the pipe 20 10 and is provided with an interior passage which connects at one end with the pipe 20 and at its other end with a chamber 31 formed interiorly of said arm; the latter supports a hollow screw 32 provided at its lower end with a vacuum brush 33 secured in place by means of a hollow head 34. The interior of the screw 32 is in communication

with the chamber 31 and consequently with the pipe 20 and the air exhausting means connected therewith by the pipe 21. A hand wheel 35 is attached to the screw 32 to raise 5 and lower, and adjust the brush 33 to and from the cone. A stop screw 36 serves to arrest the downward movement and position of the brush 33, by engagement with the flange 38 of a collar 37 which is attached to 10 the screw 32 as shown in Fig. 1.

During the wetting operation and when the hat body is removed from the cone 15 the brush 33 is elevated out of the way.

Supported by the post 20 there are shown 15 two arms 40 and 41 which support brushes 43 and 44, these brushes being supported respectively in heads 45 and 46. These heads are hollow and communicate with the hollow interior of the pipe 20.

20 The third arm 50 is shown supporting the brush 51. This arm is held, upon an extension arm 52 clamped to the post 20. The arms 40 and 41 are provided respectively with extensions 55 and 56, each of these extensions being provided with adjusting screws and nuts which strike the post 57 on the frame 5 when the brushes are adjusted 25 in their inner position.

Likewise the arm 50 is provided with an 30 extension 58 and with an adjusting screw and nut, the adjusting screw being arranged to impinge against the post 59 on the arm 52.

Each of the three arms 40, 41 and 50 is 35 pressed inwardly respectively by means of flat springs 60, 61 and 62, each one of which is pivoted at its lower end as at 63 in Fig. 1.

At the upper portions of each spring and bearing against the three arms noted, there 40 is arranged a suitable adjusting screw and nut so that the spring pressure exerted on the three arms can be modified as desired.

In order to swing the three arms outwardly 45 by the springs are swung outwardly and downwardly around the pivots 63. The brushes then may be removed from the fur body.

The operation of this apparatus is as follows. A fur hat body 17 is placed upon the 50 cone 15; the air is exhausted from the interior thereof so as to hold the hat body firmly on the cone. This cone is then rotated by means of the mechanism shown.

The three brushes 43, 44, and 51 are 55 brought to bear upon the fur body with the pressure desired; hot water is introduced through the ring 23 before the brushes have been positioned; then the cone is rotated and exhaust is exerted through each hollow 60 head of the three brushes so that during the brushing operation the fur on the exterior of the hat body will be lifted whenever the hollow portion of the brush passes over the fur of the hat body. This operation of brushing and raising nap may be 65

continued until the desired amount of nap has been raised.

Then the three brushes are removed from the cone; the exhaust from the interior of the cone is released; then the fur hat body 70 with the nap raised is removed from the cone and another one is placed thereon.

It is evident that brushes similar to those shown may be manipulated by hand instead of being held in fixed arms. I prefer, however, to use fixed brushes having a curvature adapted to the shape of the cone which varies considerably at the top and at the bottom. Hot water may be applied to the hat body at intervals during the nap raising 80 process by other means than those shown.

The invention claimed is:

1. A nap-raising apparatus comprising a 85 conform support, means for exhausting air from said support sufficiently to hold the hat body upon the support, a brush extending for a substantial distance around the support and conforming to the surface thereof, means for effecting relative scrubbing movement between the brush and the 90 support to loosen the nap of the hat body, and means for exhausting air from the portion of the hat body covered by the brush to raise the nap loosened by the brush.

2. A nap-raising apparatus comprising a 95 conform support, means for exhausting air from said support sufficiently to hold the hat body upon the support, brushes each extending for a substantial distance around the support and conforming to the surface thereof, said brushes mounted at different elevations and at different sides of the hat body, means for effecting relative movement between the brushes and the support to loosen the nap of the hat body, and means extending to said brushes for exhausting air from the portions of the hat body covered by the brushes to raise the loosened nap.

3. A nap-raising apparatus comprising a 110 conform support, means for exhausting air from said support sufficiently to hold the hat body upon the support, brushes each extending for a substantial distance around the support and conforming to the surface thereof, said brushes mounted at different 115 elevations and at different sides of the hat body, means for effecting relative movement between the brushes and the support to loosen the nap of the hat body, means adjacent to said support for wetting the hat body thereon, said brushes being movable away from the hat body, and a vacuum head to which said brushes are connected.

4. A nap-raising apparatus comprising a 125 conform support, means for exhausting air from said support sufficiently to hold the hat body upon the support, a brush extending for a substantial distance around the support and conforming to the surface thereof, a vacuum head to which said brush 130

is connected, and means for revolving said support and the hat body thereon.

5. A nap-raising apparatus comprising a coniform support, means for exhausting air from said support sufficiently to hold the hat body upon the support, a brush extending for a substantial distance around the support and conforming to the surface thereof, a vacuum head to which said brush 10 is connected, means for revolving said support and the hat body thereon, and means adjacent to said support for wetting the hat body thereon.

6. A nap-raising apparatus comprising a coniform support, means to hold the hat body upon the support, a brush extending for a substantial distance around the support and conforming to the surface thereof, a vacuum head to which said brush 20 is connected, means for revolving said support and the hat body thereon, and means for exhausting sufficient air from the revolving support to hold the hat body thereon.

7. A nap-raising apparatus comprising a coniform support, means to hold the hat body upon the support, a brush extending for a substantial distance around the support and conforming to the surface thereof, a vacuum head to which said brush is connected, means for revolving said support and the hat body thereon, means for exhausting sufficient air from the revolving support to hold the hat body thereon, and means adjacent to said support for wetting 35 the hat body thereon.

8. In a nap-raising machine, the combination with a perforated support for a hat body, of a hollow drive shaft for rotating said support, said shaft having communication with an air-exhausting pipe, and a stationary brush extending partly around said support and conforming thereto for loosening the nap on the hat body.

9. In a nap-raising machine, the combination with a perforated support for a hat body, of a hollow drive shaft for rotating said support, said shaft having communication with an air-exhausting pipe, a stationary brush extending partly around said support and conforming thereto for loosening the nap on the hat body, and means for wetting the hat body.

10. In a nap-raising machine, the combination with a perforated support for a hat body, of a hollow drive shaft for rotating said support, said shaft having communication with an air-exhausting pipe, a stationary brush extending partly around said support and conforming thereto for loosening the nap on the hat body, and means connected to the brush for exhausting air from the portion of the hat body covered by

the brush, to raise the nap which is loosened by the brush.

11. A nap-raising apparatus comprising a coniform support, means for exhausting air from said support sufficiently to hold the hat body upon the support, brushes each extending for a substantial distance around the support and conforming to the surface thereof, said brushes mounted at different elevations and at different sides of the hat body, means for effecting relative movement between the brushes and the support to loosen the nap of the hat body, means 75 extending to said brushes for exhausting air from the portions of the hat body covered by the brushes, to raise the loosened nap, and a hat-wetting device in the form of a perforated hollow ring connected to a water-supply pipe and surrounding the hat body to spray the same at intervals, said brush being movable away from the support for the purpose of exposing the entire 80 hat body to the spraying operation. 85

12. The combination of a coniform support for a hat body, a series of brushes arranged one above another and at different sides of the hat body, means for effecting relative rotation between the support and the brushes, and a round brush for the upper portion of the hat body above said side brushes, all of said brushes having a connection to an exhaust head for rasing the nap over the areas covered by the 90 brushes. 95

13. The combination of a coniform support for a hat body, a series of brushes arranged one above another and at different sides of the hat body, means for effecting relative rotation between the support and the brushes, and a round brush for the upper portion of the hat body above said side brushes, said round brush being liftable vertically from the hat body, all of 100 said brushes having a connection to an exhaust head for raising the nap over the areas covered by the brushes. 105

14. The combination of a coniform support for a hat body, a series of brushes arranged one above another and at different sides of the hat body, means for effecting relative rotation between the support and the brushes, a round brush for the top portion of the hat body above said side brushes, a shaft for the top brush, all of said brushes having a connection to an exhaust head for raising the nap over the areas covered by the brushes, said top brush and its shaft being liftable, and an adjustable stop to 110 position the brush upon the hat body. 115

Signed at Hartford, Connecticut this 21st day of April 1920.

WILLIAM A. LORENZ.
